UNITED STATES PATENT OFFICE

FREDERICK K. FILDES, OF ALTOONA, PENNSYLVANIA

CLOSURE OPERATING AND LOCKING MECHANISM

Application filed May 23, 1928. Serial No. 280,056.

The present invention relates to closure operating and locking mechanism and particularly to mechanism of this character suitable for use in connection with railway cars.

5 The invention has for its general object to provide a mechanism of the above mentioned character that is adapted to use in locking and operating the door of a sheet metal container of the kind used by railroads for shipping 10 fractional car load lots. A container of this kind is adapted to be seated on an open freight car, such as a flat car or a flat bottomed gondola car, and with other containers of the same size and construction forms an 15 independently removable unit of a multi-container car. The mechanism embodying the present invention has been particularly designed for use with containers of this type, the purpose being to provide a simple, rugged 20 and efficient mechanism which will stand up under hard usage and which can be operated with facility. The specific nature and objects 25 of the invention will become apparent hereinafter.

25 Referring to the accompanying drawings: Fig. 1 is a front elevation of a container provided with operating and locking mechanism embodying the invention;

30 Fig. 2 is a fragmentary front elevation on a larger scale showing the mechanism more in detail;

Fig. 3 is a vertical sectional view;

Fig. 4 is a detail view of the locking bolts;

35 Fig. 5 is a sectional detail of the bolt operating mechanism;

Fig. 6 is a detail elevation of the bolt operating lever mechanism;

40 Figs. 7 and 8 are sectional views taken respectively on the lines 7-7 and 8-8 of Fig. 6; and

Fig. 9 is a sectional detail taken on line 9-9 of Fig. 2.

The drawings, Fig. 1, shows a front elevation of a sheet metal container 10 of the kind referred to above, the container being provided with rings 11 secured near its upper edges for handling the container by a crane or other lifting device. The container is formed in its front side with an opening adapted to be closed by a door 12 hinged at one side on

a vertical axis. When the container is seated on the bottom of a flat gondola car the door extends within the side of the car, rendering it impossible to open the container without lifting it off the car.

55 The door 12 is formed of a steel plate reinforced by horizontal transverse ribs 13, 14, 15 and 16 of a U-shape in cross section, as clearly shown in Fig. 3, and stiffened at the edges by angle bars 18. Secured in the corners 60 formed by the horizontal flanges of the angle bars 18 and the margins of plate 12 are wooden bars 19 having beveled outer faces adapted to coact with the inclined faces of Z bars 20, which define the top and sides of the door opening, and with the inclined face of the threshold plate 24, to effect a water tight joint, the wooden bars 19 carrying a suitable packing 20 for this purpose.

65 The door is adapted to be locked by two 70 vertically arranged slidable bolts 21 and 22. The lower bolt 21, which is considerably longer than the upper bolt, passes through registering apertures in the ribs 13, 14 and 15 and through bushings 23 welded to the opposite 75 sides of angle bar 18, the angle bar of course being perforated for the passage of the bolt.

When the door is locked the lower end of bolt 21 passes through registering apertures in the threshold plate 24 and the base bar 25, the 80 extremity of the bolt being beveled to facilitate its insertion through these apertures.

85 The upper end of bolt 21 is connected by a link 26 to one arm of a rocker 27, the other arm of which is similarly connected by a link 28 to the lower end of bolt 22. Bolt 22 is slidable in apertures of rib 16 and its end projects through bushings welded respectively to angle bar 18 and to Z bar 30. The two-arm rocker 27 is fulcrumed on a post 31 which 90 has an inner threaded end extending through a hole in a plate 32 secured to ribs 15 and 16 and a nut 33 thereon for clamping the post to the plate, the other end of the post being integral with a head 34 riveted to the inside of door plate 12.

95 Bolts 21 and 22 are operated by a pawl 35 which has a rounded end 36 operating in a slot 37 formed in bolt 21. This pawl is secured on the square end 38 of a shaft 38 100

which is journaled in a bearing 40 at one side of a housing 41 and in a bearing 42 riveted to door plate 12 near the edge thereof. Housing 41 constitutes a cover for opening 43 which is necessarily formed in door plate 12 for the projection of pawl 35 through the door.

The outer end of shaft 38 is offset to form a crank 44 adapted to engage in a keeper 45 which is riveted to the container 10 adjacent the edge of the door opening. As shown more particularly in Fig. 9, the keeper comprises a hook portion 46, the inner curved surface of which is adapted to receive the crank extension 44 of shaft 38 when the door is closed and locked. The lower portion of hook 46 is formed with an inner inclined surface 46' which is adapted to be engaged by crank 44 when shaft 38 is rotated towards locking position, such engagement serving to wedge the door tightly closed. The keeper also comprises a flat vertical surface 47 opposite the hook 46. As indicated by dotted lines in Fig. 9, the crank extension 44 has a flattened inner side 48, the lower edge of which is adapted to contact the flat surface 47 of the keeper when shaft 38 has been turned through an angle of approximately 45° from the position shown in Fig. 9.

For operating shaft 38 there is provided a handle 50 which is loosely sleeved thereon. Referring to Figs. 6, 7 and 8 it will be observed that the sleeve portion of handle 50 is cut away at both sides to form radial shoulders. At the left hand side the sleeve is cut away through 180° and cooperating with the radial shoulders thus formed are oppositely facing radial shoulders, displaced 180°, formed on a sleeve 51 pinned at 52 to shaft 38. When therefore these shoulders are engaged handle 50 is clutched to shaft 38 without substantial lost motion. At the other side, the sleeve of handle 50 is cut away through an arc of 270°, forming a projection having radial shoulders 53 and 54 spaced 90°, this projection being adapted to coact with a projection having radial shoulders 55 and 56 formed by cutting away the boss of bearing 40.

Riveted to the outside of door plate 12 is a bracket 57 having a horizontally projecting staple 58 adapted to extend through a slot in handle 50 when the latter is in locked position. The staple has a perforation in its outer end adapted to receive one or more seals or a padlock, or both.

The drawings show the parts in locked position. To unlock the door, the padlock, or seal, is removed from staple 58 and handle 50 is rotated through an arc 45°, which of course rotates shaft 38 through the same angle. The rotation of shaft 38 through an angle of 45° from the position shown in the drawings is sufficient to withdraw the extremities of bolts 21 and 22 respectively

from threshold plate 24 and Z bar 30, that is, is sufficient to unlock the door. The rotation of shaft 38 through this angle brings the lower edge of the flattened portion 48 of crank 44 into contact with the flat surface 47 of keeper 45, whereupon by further rotation of handle 50 the leverage exerted by engagement of these parts loosens the door, so that the latter can be easily swung open by pulling on handle 50. The handle can now be thrown down flat against the door by sliding it to the right until its shoulders are disengaged from the shoulders of sleeve 51, it being noted that the sleeve projection at the right hand side of the handle is brought out of alignment with the projection on bearing 40 after the handle has been rotated through an arc of 45° from the position shown in the drawings. It is desirable of course to have the handle flat against the door when the latter is opened so that it will not be in the way rather than project out at an angle thereto.

Now having particularly described my invention, what I claim as new and desire to secure by Letters Patent of the United States is:

1. A door locking and operating mechanism comprising in combination, a shaft journaled in transversely aligned bearings secured to the outside of the door and having a crank portion projecting beyond the edge of the door, a keeper secured to the door frame adjacent the door opening and comprising a hook portion adapted to be engaged by the crank when the shaft has been rotated from locking position through a predetermined angle, a slidable bolt mounted on the inside of the door operatively connected to said shaft, the outer end of said bolt being adapted to engage the door frame and lock the door, rotation of said shaft through said predetermined angle being sufficient to withdraw said bolt from the frame, whereby further rotation of said shaft by engaging said crank with said abutment loosens the door, and a handle operatively connected to said shaft.

2. In combination with a sheet metal container having a sheet metal door hinged at one side on a vertical axis, a shaft rotatable in horizontally aligned bearings secured to the outside of the door and having a crank portion projecting beyond the edge of the door, a keeper secured to the container adjacent the door opening adapted to receive said crank portion, an arm secured to the inner end of said shaft and projecting through a slot formed in the door, a housing secured to the outside of the door covering said arm and slot, a vertically slidable bolt mounted on the inside of the door having a slot receiving the end of said arm, and an operating handle on said shaft.

3. In combination with a sheet metal con-

tainer having a sheet metal door hinged at one side on a vertical axis, a housing secured to the outside of the door having a bearing in one side, a bearing secured to the door adjacent the edge thereof horizontally aligned with said first mentioned bearing, a shaft rotatable in said bearings having a crank portion projecting beyond the edge of the door, a keeper secured to the container having a downwardly opening hook portion adapted to receive said crank and having an abutment opposite the hook adapted to be engaged by said crank when the shaft has been rotated through a predetermined angle from locking position, an arm secured to the end of said shaft projecting into the housing and extending through a slot formed in the door, a vertically slidably bolt mounted on the inside of the door operatively connected to said arm, and an operating handle on the shaft between said bearings.

4. A door lock comprising in combination, a shaft journaled in transversely aligned bearings secured to the outside of the door and having a crank portion projecting beyond the edge of the door, a keeper secured to the frame adjacent the door opening adapted to receive the crank, a slidable bolt mounted on the inside of the door and operatively connected to said shaft, the outer end of said bolt being adapted to engage the door frame and lock the door, an operating handle rotatable and slidable on said shaft, and means for clutching the handle to the shaft to unlock the door, the handle being slidable to disengage the clutch and permit the handle to be turned down flat against the door after it has performed its unlocking function.

5. A door lock comprising in combination, a shaft journaled in transversely aligned bearings secured to the outside of the door and having an eccentric portion projecting beyond the edge of the door, a bolt mounted on the inside of the door and operatively connected to said shaft, the outer end of said bolt being adapted to engage the door frame and lock the door, an abutment on the door frame engaged by the eccentric portion of said shaft when the latter has been rotated through a predetermined angle from its locking position, and a handle operatively connected to said shaft, the parts being so constructed that when said shaft has been turned through said predetermined angle from locking position said bolt will be withdrawn from locking engagement with the frame, whereupon on further rotation of the shaft engagement of said eccentric portion with said abutment will loosen the door so that it can be easily swung open by pulling on the handle.

6. In combination with a sheet metal freight container of the kind described, a sheet metal door hinged on a vertical axis, a housing secured to the outside of the door

formed with a transverse bearing in one side, a bearing secured to the door near the edge thereof, a shaft journaled in said bearings formed with a crank portion projecting beyond the edge of the door, a keeper secured to the container adjacent the door opening adapted to receive said crank, a vertically extending bolt slidably mounted on the inside of said door, an arm secured to said shaft inside said housing projecting through a slot formed in the door, said bolt having a slot engaged by the extremity of said arm, the outer end of said bolt being adapted to engage the door frame to lock said door, an operating handle rotatable and slidable on said shaft between said bearings, means for clutching the handle to said shaft, the handle being slidable to disengage said clutching means so that the handle can be rotated relatively to the shaft.

In testimony whereof I hereunto affix my signature.
